UNITED STATES PATENT OFFICE.

FRANK JAMES ELVY, OF CATFORD, LONDON, ENGLAND.

BOAT AND THE LIKE.

1,383,392.

Specification of Letters Patent.

Patented July 5, 1921.

Application filed November 4, 1920. Serial No. 421,635.

To all whom it may concern:

Be it known that I, FRANK JAMES ELVY, a subject of the King of Great Britain and Ireland, and resident of Catford, London, 5 England, have invented certain new and useful Improvements in Boats and the like, of which the following is a specification.

This invention relates to ships' boats and the like and has for its object to reduce the 10 height required for stowing, one above another, a given number of boats of a given height, and to obviate the employment of the usual transversely disposed bilge chocks.

In the present system of stowing boats 15 on the decks of ships each boat usually rests with either end on a pair of chocks hinged to a skid, and if it be desired to save deck space by stowing boats one above another, the skids carrying the upper boats are usually supported by frames extending from 20 the deck clear of the lower boat or boats. This system, especially when the boats have a deep hanging keel, necessitates the use of very high and massive davits and constitutes 25 additional expense. Another disadvantage is that the whole weight of the boat is carried by the planking of the hull, which is liable to bulge between the pairs of chocks thus making the boat unseaworthy.

30 In accordance with this invention boats provided with side keels extending fore and aft in vertical planes and downwardly to the level of or lower than the bottom of the central keel, have thwarts which are 35 strengthened by means of metal frames or by pillars and stiffeners extending vertically above the side keels and secured each by one end to a keelson and by the other to a thwart in order that any weight on the thwarts *e. g.* 40 due to a boat or boats resting thereupon may be transmitted directly to the keelsons.

If desired, further support may be provided by securing pillars between the central keel and the thwarts, the latter and also 45 the deck of the ship being provided with chocks adapted to receive the central keel. Shaped planks lying vertically above the side keels may be secured on top of the thwarts, said planks being adapted to support the side keels of a similar boat.

50 My invention is illustrated in the accompanying drawings, in which Figure 1 is a side elevation of a boat; Fig. 2, a transverse section on the line 2—2 of Fig. 1, and

Fig. 3 is a partially broken away section of 55 a modified construction.

According to one form of the invention as illustrated by the accompanying drawings whereof Fig. 1 is an elevation of a boat and Fig. 2 is a section on line 2—2 Fig. 1 to 60 an enlarged scale a boat having a thick plank *a* in place of the usual keel is provided with two side keels, *b*, *b* on opposite sides of the plank *a* and at a suitable distance from it, each of the side keels *b*, *b* 65 extending vertically downward to the level of the bottom of the plank *a* and extending longitudinally of the boat for a distance of half or five-eighths of the length of the boat as shown in Fig. 1. Each of the side 70 keels *b*, *b* is secured to a shaped plank *c* which extends beyond each end of the side keel *b* and which together with the side keel *b* is secured to a bilge keelson *d* by means of bolts *e* or the like passing through 75 the ribs *f* of the hull. Vertically extending wooden pillars *g* are secured by one end to the bilge keelson *d*, the other end of each pillar *g* being secured to a thwart *h*, and each of the pillars *g* is strengthened by a box- 80 ended angle-iron *j* secured therewith, and similar pillars *l* are provided centrally of the thwarts *h*, the lower ends of said central pillars bearing on the keelson *m*.

A plank *n* lying vertically above each side 85 keel *b* extends fore and aft across the thwarts *h* and on top of the side seat *o* and is secured thereto, said planks *n* being adapted to support the side keels *b* of another similar but shorter boat which may be stowed above 90 the first. Bearers *p* are provided centrally of the thwarts and vertically above the pillars *h*, recesses being provided therein for the reception and support of the plank *a* of said shorter boat.

95 Fig. 3 illustrates the invention as applied to a boat having the usual keel *r*.

When such boats are stowed one above the other, the weight of the boats is transmitted to the deck *q* of the ship or other surface 100 directly through the side keels *b* and pillars *g* thus relieving the hull *f* from strain.

The construction enables boats to be stowed with a minimum of head room and deck space and prevents damage to the boats 105 due to excessive pressure on the hull; this feature is of especial importance for motor boats.

A further advantage lies in the fact that the side keels *b* may be provided with suitable hand grips *s* for use in case of capsizing, thus adding to the safety of the boat.

5 The davits may be shortened and made lighter or alternatively they may remain of normal size, when greater freedom of movement is available.

I claim:—

- 10 1. A boat having a central keel, side keels extending fore and aft in vertical planes and downwardly at least as far as the level of the bottom of said central keel, keelsons above each of said side keels, thwarts, supports vertically above each of said side keels, said supports being secured between said keelsons and said thwarts and adapted to transmit directly to said keelsons any weight on said thwarts.
- 15 2. A boat having a central keel, side keels extending fore and aft in vertical planes and downwardly at least as far as the level of the bottom of said central keel, keelsons above each of said central and side keels, thwarts, supports vertically above each of said central and side keels, said supports being secured between said keelsons and said thwarts and adapted to transmit directly to said
- 20 3. A boat having a central keel, side keels extending fore and aft in vertical planes and downwardly at least as far as the level of the bottom of said central keel, keelsons above each of said side keels, thwarts, supports vertically above each of said side keels, said supports being secured between said keelsons and said thwarts and adapted to transmit directly to said keelsons any weight on said thwarts, and shaped planks secured on top of said thwarts and vertically above said side keels, said shaped planks being adapted to support the side keels of a similar boat.
- 25 4. A boat having a central keel, side keels extending fore and aft in vertical planes and downwardly at least as far as the level of the bottom of said central keel, said side keels being provided with hand grips, keelsons above each of said side keels, thwarts, supports vertically above each of said side keels, said supports being secured between said keelsons and said thwarts and adapted to transmit directly to said keelsons any weight on said thwarts, substantially as set forth.

FRANK JAMES ELVY.
